P. A. WARD

SOLE AND STITCH REMOVING MACHINE

Filed Dec. 12, 1923

INVENTOR.
Paul A. Ward
By Lester A. Mack
Attorney.

UNITED STATES PATENT OFFICE.

PAUL A. WARD, OF LOS ANGELES, CALIFORNIA.

SOLE AND STITCH REMOVING MACHINE.

Application filed December 12, 1923. Serial No. 680,124.

To all whom it may concern:

Be it known that I, PAUL A. WARD, a citizen of the United States, and a resident of Los Angeles, county of Los Angeles, State 5 of California, whose post-office address is 251 N. Grand Avenue, Los Angeles, California, have invented new and useful Improvements in Sole and Stitch Removing Machines, of which the following is a specification.

This invention relates to a sole and stitch removing machine, particularly useful in a shoe repair shop, for cutting and removing the sole from the welt of a shoe, and for 15 cutting and removing the stitches from the welt in a single and simultaneous operation preparatory to re-soling a shoe.

In the consideration of this invention, reference is had to my pending application 20 for patent for sole and stitch removing machines, filed August 6, 1923, Serial No. 655,990.

The main object of the present invention is to provide a machine partaking of the 25 general form and characteristics of the machine described in my said pending application but provided with oscillatable cutting and stitch removing elements, whereas, in my said pending application I have shown 30 certain elements rotatably arranged.

A further object of my invention is to provide a combined sole and stitch removing machine in unitary form and provided with a knife adapted to be inserted between the 35 welt and the sole of a shoe for cutting the stitches which hold the welt and sole together, so that the sole may be quickly removed from the shoe, together with a stitch removing element adapted to engage the exposed portions of the stitches immediately 40 after the same have been cut, for removing the cut stitches from the welt.

Another object is to provide a machine 45 of the character described, alternately operable sole and stitch removing elements adapted for oscillation or reciprocation relative to the sole and welt of a shoe when the shoe is being operated upon for the purpose mentioned.

Still another object is to provide a machine of unitary character and compact form and simple design for use in shoe repair shops for the purpose described. Other 50 objects may appear as the description progresses.

I have shown one practicable and preferred form of device for accomplishing the above objects in the accompanying drawing, in which:

Fig. 1 is a side elevation of my assembled 60 machine.

Fig. 2 is a slightly enlarged front elevation of the same, partly broken away.

Fig. 3 is a fragmentary plan.

Fig. 4 is an enlarged sectional plan of 65 the machine as seen on line 4-4 of Fig. 3.

Fig. 5 is a section of same on line 5-5 of Fig. 4.

Fig. 6 is a section of same on line 6-6 of Fig. 4. 70

Fig. 7 is a section of same on line 7-7 of Fig. 4.

Fig. 8 is a perspective view of the stitch removing tool.

Fig. 9 is a perspective view of the sole 75 cutting tool.

Fig. 10 is a transverse section on line 10-10 of Fig. 3.

As shown in the drawing, my improved machine includes a suitable cast metal stand 80 S which is provided with a bracket b, on which is mounted a motor M. The upper end of the stand S has a pair of transversely aligned bosses 1 and 2, which are spaced apart and are adapted to revolvably receive 85 and hold an operating shaft 3. One end of shaft 3 is extended from boss 1 and has attached thereto a driven pulley P which is operatively connected by means of a belt B with a driving pulley P' fixed to the shaft 90 of motor M.

The stand S also has a substantially elongated boss 4, which parallels and is spaced from the boss 2 and is formed on the upper end of the stand. Boss 4 is adapted 95 to receive a stud 5 which is substantially extended from the outer end of the boss and carries a sleeve 6 which abuts the end of said boss. A stitch removing arm A is adjustably held on the sleeve 6 at 1 by 100 means of a pin 7 which extends through a portion of arm A, and the adjacent end of said arm is provided with a slot 8 which overlies the sleeve 6.

This structure described is such that the 105 arm A may swing about the axis of pin 7 on sleeve 6 for purposes hereinbefore described.

The operating shaft 3 has its outer end in the form of a crank C with an inner eccentric 110

tric portion e , an outer eccentric portion e' and an intermediate concentric portion C' . The end portion of the arm A which is remote from the stud 5 is provided with an elongated slot 9 which is adapted to receive the inner eccentric portion e of crank C' so as to effect the oscillation of arm A about the axis of stud 5. The crank operated end of arm A is provided with a stitch removing tool T, as shown in Fig. 8, which has a base portion 10 adapted to fit over the end of arm A and to be attached thereto by means of a screw 11 inserted through a suitable aperture 12. Tool T also has a depending flange 13 which engages the inner side of arm A so as to prevent the turning of the tool on the arm.

The vertical portion 14 of tool T has a plurality of radially formed stitch removing teeth t , t etc., said teeth being of segmental cross-section and having their outer faces of convex form and adapted to engage the stitches in the welt of a shoe after the same have been cut.

Stud 5 also pivotally carries on arm A' which is similarly oscillatable about the axis of stud 5, and the opposite end of arm A' has an elongated slot 15 which is received and held by the eccentric portion e' of crank C' . The eccentric operated end of arm A' carries a sole cutting knife or tool T' which has a knife K extended outwardly from a flat base portion 16. Tool T' is adapted to be mounted on the end of arm A' and held by means of a screw 17 which extends through an aperture 18 formed in the base of the tool and, as in the case of tool T, a depending flange 19 is provided on the base of the tool for engagement with the side of arm A' , so as to hold the inner face of the knife parallel with the operating faces of the switch removing teeth t , t etc. of tool T.

Intermediate the arms A and A' a guard member G is held on the outer portion of stud 5 which extends through the hub 20 of said guard, while the opposite end of the guard has its hub 21 fixedly held on the concentric portion C' of crank C. Said guard however, has a knife like plate extension g which is beveled and is held in close contact with the knife K as shown in Fig. 3.

Now, it will be observed by reference to Fig. 4, that the operating shaft 3 is substantially extended from the boss 2 on stand S, and adjacent said boss a collar 22 is fixedly held by means of a set screw 23, while a cup-like member D is loosely held on shaft 3 and overlies a substantial portion of, and is slideable on collar 22. The bore 24 of member D, intermediate the outer end 25 thereof, and collar 22, is adapted to receive a cushion E, of rubber or the like, and the arrangement of the members 22, D and E are such that ample clearance may be provided between

the inner end of member D and the outer end of boss 2. Member D is adapted to be rotated by means of a pin 25 held in the collar 22 and extended through an elongated slot 26, in the wall of member D.

Now in operation, when it is desired to cut the sole from the welt and remove the old stitches therefrom, the sole is held edge-wise relative to the tools T and T' with the upper side of the sole in engagement with the tool T, and so that the cutting edge of the knife K will operate in the plane of the joint between the welt and the sole, as shown in the drawings.

It will be observed that the eccentric portions e and e' have their axes on a diametrical line, cutting the axis of the concentric portion C' , so that they will operate the arms A and A' respectively, in opposite directions. The slots 9 and 15 in members A and A' prevent the movement of said arms horizontally but permit the movement thereof vertically, and the tool T will always move in a direction opposite to that of tool T' .

When the shoe is held in engagement with tools T and T' , as stated, the knife K will serve to cut the sole from the welt, and on the succeeding movement of tool T the stitches, which have been previously cut, will be removed from the welt by reason of the frictional engagement of the teeth t on the tool T therewith.

As the operation progresses the shoe is turned so that different portions thereof, will be operated upon successively by the tools T and T' until the sole has been completely cut from the welt and the stitches have been removed.

The mechanism described is so arranged that the tools T and T' will be spaced apart to accommodate a minimum thickness of sole, but for soles of greater thickness said tools may be spread apart to a proper extent by forcing the shoe between and against the tools, which will serve to move the innermost arm A and its tool T inwardly until the cushion E will be compressed to a corresponding extent while the member D will slide over the collar 22 so as to accommodate the mechanism to soles of different thickness.

As hereinbefore stated, the arm A may be further adjusted on its axis 7 for more perfectly accomplishing the adjustment of the tool T. The members A, A' and G are operatively held on the shaft 3 and stud 5 by means of screws 28 and 29 which are threaded into the ends thereof.

It will be understood that I may modify and otherwise change my invention within the scope of the appended claims without departing from the spirit thereof.

What I claim is:

1. A machine of the character described comprising a cutting element for severing

the stitches connecting a welt with a sole, a stitch removing element for engagement with the welt for removing the severed stitches, and means for operating said elements.

2. A machine of the character described comprising a cutting element for severing the stitches connecting a welt with a sole, a stitch removing element for engagement with the welt for removing the severed stitches, and means for operating said elements in opposite directions.

3. A machine of the character described comprising a cutting element for severing the stitches connecting a welt with a sole, a stitch removing element for engagement with the welt for removing the severed stitches, and means for operating said elements, and means for yieldably supporting one of said elements relative to the other.

4. A machine of the character described comprising a cutting element for severing the stitches connecting a welt with a sole, a stitch removing element for engagement with the welt for removing the severed stitches, and means for operating said elements in opposite directions, and means for yieldably supporting said elements relative to each other.

5. A machine of the character described comprising an oscillatable cutting element, a reversely operable stitch removing element, and means for continuously operating said elements in opposite directions, for the purpose described.

6. A machine of the character described comprising an oscillatable cutting element, a reversely oscillatable stitch removing element and means for continuously operating said elements in opposite directions, and means for yieldably supporting said elements relative to each other.

7. A machine of the character described comprising a cutting element for severing the stitches between a welt and a sole, a stitch removing element for removing the severed stitches from the welt, and a guard

between said elements arranged in operative relation with respect to said cutting element, and means for operating said cutting and stitch removing elements.

8. A machine of the character described comprising a cutting element for severing the stitching between a welt and a sole, a stitch removing element for removing the severed stitches from the welt, a guard between said elements arranged in operative relation with respect to said cutting element, means for operating said cutting and stitch removing elements, and means for yieldably supporting said stitch removing elements relative to said cutting element.

9. A machine of the character described including a driven member, a cutting tool, operatively connected therewith, a stitch removing tool also operatively connected with said driven member, and spaced from said cutting tool, and means for actuating said cutting and stitch removing tools synchronously and in opposite directions, for the purpose described.

10. A machine of the character described including a driven member, a cutting tool, operatively connected therewith, a stitch removing tool also operatively connected with said driven member and spaced from said cutting tool, and means for actuating said cutting and stitch removing tools synchronously and in opposite directions, and a guard operatively engaging said cutting tool.

11. A machine of the character described including a driven member, a cutting tool, operatively connected therewith, a stitch removing tool also operatively connected with said driven member and spaced from said cutting tool, means for actuating said cutting and stitch removing tools synchronously and in opposite directions, and means for yieldably supporting said tools relative to each other.

PAUL A. WARD.
